POP-UP TOY

Kathryn E. Wilkening, Bryn Mawr, Pa., assignor to Wilkening Manufacturing Company, Philadelphia, Pa., a corporation of Delaware

Application February 1, 1957, Serial No. 44,711

Term of patent 7 years

(Cl. D34—15)

I claim:

The ornamental design for a pop-up toy, as shown and described.
